UNITED STATES PATENT OFFICE

GEORGE H. CHAMBERLAIN, JR., OF ELYRIA, OHIO

STEAM GENERATING DEVICE

Application filed March 30, 1928. Serial No. 266,083.

This invention relates to an improved steam generating device.

The steam generating systems which are familiarly used in the heating of private residences and other buildings, comprise a boiler and a furnace for raising the temperature of the water contained in the boiler to the degree necessary for the hot water or steam system, the entire body of water being heated as a whole and at one time. As a result, the development of the necessary degree of steam is comparatively slow. Furthermore, this old system occupies a considerable area in the basement or wherever installed and it is comparatively inefficient with regard to the amount of heat required for a given temperature in a given system.

Accordingly, it is the object of the present invention to devise a steam generating device which is not only compact and more attractive in appearance than the old system, but which is at the same time, more efficient with respect to the speed with which steam may be developed and supplied to the system of radiators; and at the same time, to devise such a system which is designed in such a manner as to conserve the heat employed for development of the steam.

Other objects will appear from the following description and claims when considered together with the accompanying drawing.

Fig. 1 is a partial view of a heating system of which my improved steam generating device forms a part; and Fig. 2 is a vertical sectional view of the steam generating device itself.

The main body of my improved device comprises a single casting which has the outer wall 1 and the inner wall 2, the space between these two walls serving as a chamber for the water and the steam which is received in the upper portion thereof. As clearly indicated in the drawing, the outer wall is of substantially cylindrical shape with its top portion formed as a dome, while the inner wall 2 tapers upwardly and inwardly. The water supply pipe is indicated by reference numeral 3 and is provided with a suitable valve 4 and pipe connection 5 com-

municates with the bottom of the water-containing chamber. Suitable connection is provided at the point 6 for the spiral copper tube 7 which is housed within the fire chamber inside the inner wall 2. The upper end of the tube 7 has connection through the upper end of the inner wall 2 with the steam chamber in the dome portion already referred to.

As will be observed from the drawing, the diameter of the spiral of the tube 7 decreases upwardly while the inclination of the convolutions of the spiral increases accordingly. The purpose of this feature is to render as uniform as possible the rate of travel of the water through the tube at all points.

The burner 8 has connection with the gas supply pipe 9 and is arranged immediately under the bottom end of the spiral tube 7 and surrounds the lower vertical portion of the tube 7, as clearly indicated in Fig. 2. This burner may be supported in any suitable manner. The tapering form of the inner wall 2 tends to converge the heat as it rises and in this way, serves to compensate for the distance of the upper part of the tube 7 from the burner. As a result, the degree of heating is rendered more nearly uniform at all points of the tube 7. The waste gases from the burner are discharged through the outlet 10.

The water which passes through the tube 7 is rapidly converted into steam which is discharged through the upper end of the tube 7 and received into the steam chamber under the dome. The baffle 11 is of a substantially circular form and has its under side curved upwardly and outwardly from a central point, as indicated in Fig. 2, so as to deflect the steam as it passes through the upper end of the tube 7. This baffle not only prevents a sudden gush of steam through the dome but also permits any wet steam or condensation to find its way back into the water chamber rather than be transmitted out through the steam pipe to the radiators. The baffle 11 may be mounted by means of legs upon the top of the inner wall 2 and may be inserted for installation through the handhole in the top of the dome. This handhole is closed by

the cover 12, into which is threaded the pipe 13 which leads to the system of radiators.

The steam upon being received in the steam dome, is transmitted through the pipe 13 to the radiators, one of which is indicated by reference numeral 14, and the water of condensation is returned through the pipe 15 to the water supply. Thus, the circuit is complete, and this device may be operated for a comparatively long time without requiring replenishment of water.

This device is provided also with the water gauge 16, the vacuum and steam gauge 17, the pop valve 18, the thermostat 19, and the thermostat control motor 20, together with the pilot 21.

In actual use, the water chamber is filled to the proper point, as indicated, for instance, in Fig. 2, and the heat then applied for the development of steam. Because of the particular structure and arrangement of the comparatively small spiral tube, through which passes a comparatively fine thread of water immediately above the heat, steam is developed at an exceedingly rapid speed. This is made possible by virtue of the fact that this comparatively fine thread of water is subjected to the full intensity of the heat, the surface area of the water being thereby increased to an approximate maximum for exposure to the heat, and this comparatively fine stream of water is moved at a comparatively high rate of speed so that a certain portion of the water is at one instant developed into steam and is at once conveyed as steam to the steam chamber or dome so as to permit a fresh supply of water to be subjected in the same manner to the same degree of heat. In other words, a greatly increased surface area of the water is subjected in the form of a comparatively fine and rapidly moving thread to the full intensity of the heat instead of subjecting a large body of water for a comparatively long time to the heat, as is true of the old system.

Furthermore, with the present jacketed arrangement, in which the water chamber surrounds the fire chamber, there is conserved a large portion of the heat which would otherwise be lost.

It is to be understood that with the thermostat arrangement here disclosed, the device may be set for the desired temperature and the automatic control depended upon in the same manner as already known in other heating systems.

This device may be supported upon the legs 22 and a heat-insulating cover 23 is provided about the main body of the steam generating device. If so desired, the dome portion may be formed separately from the main cylindrical body portion, although as here shown, the entire body portion including the inner and outer walls throughout the entire height thereof, is formed as a single casting. Suit-

able connections are provided for the several pipes, as indicated in the drawing.

The present device recommends itself because of its compact form and consequently neat appearance and also because of its high degree of efficiency in conserving the heat, thereby reducing the waste of heat units, and also because of the comparatively high rate of speed with which the steam may be generated for distribution throughout the radiator system. It is to be understood, furthermore, that this device may be employed not only in connection with radiator systems for heating residences, etc., but is capable of general application and may be used for the generation and distribution of steam wherever desired.

Furthermore, with proper modification, my present device, with the same general principle and high degree of efficiency, may be adapted for use in the development of hot water, instead of steam, for a hot water heating system. This modification would entail also a variation as to the degree of heat applied to the water.

What I claim is:

1. A steam-generating device comprising a converging heating chamber, a water and steam chamber surrounding said heating chamber, a correspondingly tapering spiral fluid-conveying means extending through said heating chamber and having communication with said water and steam chamber, and the inclination of successive convolutions of said spiral progressively increasing toward the top of the coil.

2. A steam generating device comprising a water and steam chamber having spaced inner and outer walls, a re-entrant heating chamber within said inner wall, an upwardly tapering, spiral fluid-conveying coil in said heating chamber, the inclination of the successive convolutions of said spiral progressively increasing towards the top of the coil, a water supply pipe having connection to the lower ends of the said chamber and coil and affording communication between said chamber and coil so as to supply water from the chamber to the coil, said coil having communication with said chamber through the upper end of said inner wall so as to deliver steam to said chamber, said chamber having a steam outlet, and fluid-circulating pipe connections between said steam outlet and said water supply pipe connection at the bottom of said chamber.

In testimony whereof, I hereby affix my signature.

GEORGE H. CHAMBERLAIN, JR.
